UNITED STATES PATENT OFFICE.

JOHN MUNKACSY, OF NEWARK, NEW JERSEY, ASSIGNOR OF ONE-HALF TO FRANK J. FIBISH, OF BOGOTA, NEW JERSEY.

SAFETY APPLIANCE FOR ELEVATORS.

1,117,887.

Specification of Letters Patent. Patented Nov. 17, 1914.

Application filed March 3, 1914. Serial No. 822,153.

To all whom it may concern:

Be it known that I, JOHN MUNKACSY, subject of the King of Hungary, resident of Newark, in the county of Essex and State 5 of New Jersey, have made a certain new and useful invention in Safety Appliances for Elevators; and I declare the following to be a full, clear, and exact description of the same, such as will enable others skilled in 10 the art to which it appertains to make and use the invention, reference being had to the accompanying drawings, and to letters or figures of reference marked thereon, which form a part of this specification.

15 Figure 1 is a central vertical section of an elevator on the line 1—1, Fig. 2, showing the invention as applied. Fig. 2 is a bottom plan view of the elevator, partly broken away, showing the invention as applied and 20 partly in section. Fig. 3 is a detail side view of the rack and pinion. Fig. 4 is a detail bottom plan view partly broken away, of the invention as applied showing a modification. Fig. 5 is a detail plan view of the 25 double pawl of the modification.

The invention has relation to safety appliances for elevators, having for its object to provide improved mechanically controlled means for stopping the elevator car 30 instantly or nearly so upon release or breakage of the support for said car.

Other objects and advantages will herein-after appear.

The invention consists in the novel construction and combinations of parts, as hereinafter set forth.

In the accompanying drawings, illustrating the invention, the numeral 1 designates an elevator car, 2 the usual support from 40 which the car is suspended, 3 the usual vertical rack in the elevator shaft, and 4 the pinion working in said rack and carried by the elevator car, below the same.

5 is a clutch member, preferably a ratchet wheel, mounted upon the shaft 6 of the pinion and rotating with said shaft.

8 is a complementary clutch member, in the present case a pawl, for engagement with said ratchet, said pawl being also carried by the elevator car, below the same, and being normally held released from the ratchet by suitable means of connection with the overhead support, said connection being preferably a flexible rope or wire 9, provided 55 with a protecting covering or tube 10. The

support 2 includes usually a flexible link 11, normally upright, the flexible connection 9 having attachment at the upper end of the link, or so that when the support is in normal position tension will be exerted upon 60 the wire 9 to lift the pawl from the ratchet, but should release or breakage of the support occur, link 11 will drop, tension upon the wire being released, and the pawl will immediately fall into engagement with the 65 ratchet and check the rotation of the same, of the shaft and of the pinion working in the rack, and hold the pinion and the elevator car stationary, so far as descent of the car in the elevator shaft is concerned. A spring 70 11' will usually be employed to insure engagement of the pawl with the ratchet wheel in the case stated.

In order to relieve the strain upon the pinion and to provide braking means co- 75 operating with the clutch means in bringing the car to a stop, said braking means having stronger engagement the more the pawl may yield in its ratchet, the pawl is usually provided with a pin and slot connection 12 with 80 the elevator car, a slide bar 13 having at one end a pivotal connection 14 with the tail of the pawl, said slide bar having movement in a bracket or support 15 secured to the car bottom and at its other end having 85 a guide bracket 16 normally engaging an upright bar 17 in the elevator shaft, opposite the rack bar. In this way when the pawl is engaged with the ratchet, the slide bar will force the guide bracket against the 90 bar 17, so that a braking action of the bracket upon the said bar will be effected. A comparatively slight movement of the pawl is allowed.

In Fig. 2 of the drawings the application 95 of the invention is shown to old elevator apparatus, and in Fig. 4 to new elevator apparatus. In the latter case, duplicate pawl and ratchet means 5 and 8 will be provided, the two pawls having a transverse 100 connection rod 18 and the slide bar 13 having attachment centrally of said rod. In this way the guide bar 17 at the same side of the elevator shaft as the rack bar may be dispensed with, the rack bar 3 acting 105 also as a guide bar. Both pawls are released by one wire 9, said wire having attachment centrally of a rod 19, connecting the two pawls.

The invention is to be applied below the 110

floor of the car, to insure the stoppage even though the upper part of the car may be torn off with the overhead support. The overhead support 2 is preferably provided 5 with a spring connection 20, to exert downward tension upon said support, so that in case of any unusual yielding of the support without positive breakage thereof, the safety clutch will be set, and the elevator stopped.

10. What I claim is:—

1. A safety appliance for elevators having a vertical rack bar and an opposite vertical guide bar in the elevator shaft, a pinion carried by the car and working in said rack 15 bar, and an overhead support for the car, said appliance comprising a ratchet rigidly mounted upon the shaft of said pinion, a pawl upon the car, means connecting said pawl with said support and normally holding 20 said pawl from engagement with said ratchet, and a brake shoe having connection with said pawl and adapted for engagement with said guide bar.

2. A safety appliance for elevators having a vertical rack bar and an opposite vertical guide bar in the elevator shaft, a pinion carried by the car below the floor of the same and working in said rack bar, and an overhead support for the car, said appliance 30 comprising a ratchet rigidly mounted upon

the shaft of said pinion, a pawl slidably mounted beneath the car, means connecting said pawl with said support and normally holding said pawl from engagement with said ratchet, and a brake shoe having connection with said pawl and adapted for engagement with said guide bar.

3. A safety appliance for elevators having a vertical rack bar and an opposite vertical guide bar in the elevator shaft, a pinion carried by the car and working in said rack bar, and an overhead support for the car, said appliance comprising a ratchet rigidly mounted upon the shaft of said pinion, a pawl having slot and pin connection with the floor of the car, means connecting said pawl with said support and normally holding said pawl from engagement with said ratchet, a guide bearing beneath the floor of the car, a slide having movement therein and pivotal connection with said pawl, and a brake shoe upon said slide adapted for engagement with said guide bar.

In testimony whereof I affix my signature, in presence of two witnesses.

JOHN MUNKACSY.
